MANUAL CONTROLLED DEVICE FOR AUTOMATIC CIRCUIT RECLOSE MECHANISMS

James K. Harper, Centralia, Mo., assignor to A. B. Chance Company, Centralia, Mo., a corporation of Missouri

Application February 11, 1948, Serial No. 7,604

4 Claims. (Cl. 209—89)

1

The present invention relates to manual controlling devices for automatic circuit recloser mechanism, and is particularly concerned with the manual controlling devices for the mechanism disclosed in the prior application of David C. Hubbard, Serial No. 740,687, filed April 10, 1947, for Automatic Circuit Recloser Mechanism.

The recloser mechanism referred to is a circuit maker and breaker of the type which is adapted to be immersed in an insulating liquid, such as oil. For a full disclosure of the automatic circuit recloser mechanism with which these controlling devices are to be used, reference may be had to the prior application above mentioned, the general purposes and characteristics of which will now be set forth insofar as they have a bearing upon the manual controlling devices.

The circuit recloser mechanism is preferably of the type in which an overload causes a fast opening of the circuit on the first and second occurrences of an overload, but which interposes a time delay before the opening of the circuit on the third and fourth occurrences of an overload. After the third or fourth operation the mechanism is preferably provided with means for holding the circuit breaker in the open position so that it can only be closed by a manual operation.

The overload conditions which may cause the opening of such an overload protection device, may be temporary and, if temporary, the circuit may again be closed automatically without waiting for attention upon the part of the lineman. This automatic closing of the circuit for temporary line faults increases the service continuity and reduces the areas which are cut out of service, due to overload, to the smallest possible area.

If, however, the circuit condition which has caused an overload is not temporary, or if it requires a longer time to correct itself, then it is desirable that the overload mechanism be closed automatically only after a time delay. Such a time delay is brought about by permitting automatic recloser to operate more than once, or by providing a time delaying mechanism. If, however, after a time delay the fault has not been corrected the provision should be made for preventing the reclosing mechanism from reclosing the circuit again and again.

One of the objects of the invention is the provision of an improved manual controlling mechanism for automatic circuit reclosers, which gives a visual indication when the contacts are open so that the serviceman may see the condition of the device.

Another object of the invention is the provision of an improved manual controlling device for

2

automatic circuit reclosers which permits the recloser to operate and reclose the circuit twice, and also to reset itself after a time delay on the third or fourth operation.

Another object of the invention is the provision of an improved manual controlling device for automatic circuit reclosers which devices are trip-free, so that after a lock-out of the circuit breaker, when the contacts are reclosed manually while the short circuit or overload still continues, the contacts may be opened automatically even though the operator is holding the manual devices in the closing position.

Another object of the invention is the provision of an improved mechanism, which permits the circuit recloser to reset itself for a normal four-cycle operation whether the contacts are closed manually after lock-out, or whether the contacts are closed automatically after a momentary fault of insufficient duration to cause a lock-out.

Another object of the invention is the provision of an improved mechanism of the class described, which permits the contacts to be opened manually into the lock-out position at will.

Another object of the invention is the provision of an improved mechanism of the class described, which may be used with a single unit or line or which is adapted to be used for a three-phase circuit recloser, so that a fault on any phase will open the contacts on all three phases simultaneously to prevent damage to three-phase equipment, such as electric motors.

Still another object of the invention is the provision of an improved mechanism of the class described, which is simple in construction, durable, adapted to be used for a long period of time without necessity for repair or replacement of any of its parts, and is adapted to be manufactured economically so as to reduce the cost of the equipment to the consumer.

Other objects and advantages of the invention will be apparent from the following description and the accompanying drawings, in which similar characters of reference indicate similar parts throughout the several views.

Referring to the two sheets of drawings accompanying this specification,

Fig. 1 is a vertical sectional view taken through the automatic circuit recloser mechanism on a plane passing through the axis of the solenoid plunger and the axis of the time delay cylinder;

Fig. 2 is a fragmentary top plan view of the mechanism of Figure 1 in partial section, on a plane passing through the axis of the controlling shaft for the manual controlling devices;

Fig. 3 is a fragmentary vertical sectional view

similar to the upper part of Figure 1, with the mechanism in open circuit position in which it has been locked;

Fig. 4 is a sectional view taken on the plane of the line 4—4, of Figure 2, looking in the direction of the arrows, and showing the lost motion mechanism which is located between the manual controlling device and the automatic circuit recloser, one of its positions;

Fig. 5 is a similar view, with this lost motion mechanism in a second position;

Fig. 6 is a third similar view, with the mechanism in a third position; and

Fig. 7 is a fragmentary horizontal sectional view similar to Figure 2, but showing the mechanism required for a three-phase circuit.

Referring to Figure 1, I shall first describe the automatic circuit recloser mechanism with which the present manual controlling devices are intended to be used. This recloser mechanism is intended to be submerged in an enclosed tank 9 in oil, the leads being brought out the top of the tank through elongated multiskirt insulators, the tank being grounded, and separate lightning arresters being provided between the ground of the tank and the conductor at the end of each insulator.

The present device preferably includes a supporting spool 10 for an overload coil 11, the spool having a central bore 12 for receiving the substantially cylindrical armature 13. The assembly is carried by the cover of the enclosing tank, from which it depends. The spool 10 supports a housing member 14 which includes a cylinder 15 having an inner cylindrical chamber 16 serving as a dash pot.

The dash pot piston 17 may comprise a disk 18 having a suitable clearance with respect to the cylindrical wall 16, and having a hub 19 with a bore 20 for receiving the armature 13 to which it is riveted by the rivet 21. Flanges are extended to form fins 23 which project laterally from two slots 24 in the cylinder wall 15 for supporting a pair of snap springs 25 by means of which the movable contacts are actuated.

The housing 14 also includes a laterally extending, U-shaped portion 26 comprising a pair of parallel walls 27, and the end wall 29. This U-shaped portion may be open at its top and bottom for access of oil to the contacts. The left wall 30, between this U-shaped portion and the cylinder 15, may be thickened toward the top to provide a diagonally and upwardly extending stop surface 31 for limiting the motion of the switch arm. The lower portion of this wall supports a pair of pivot flanges 32 for receiving the switch arm 34, which preferably consists of an insulating shield.

The switch arm or shield 34 may consist of a laminated member of indurated fiber which is impregnated with a phenolic condensation compound, and which may be a sector, being provided at its axis with an aperture 35 for receiving the rivet or pintle 36 by means of which it is pivoted between the flanges 32.

The contact arm 34 supports adjacent its upper edge 37 a bridging contact 38. The projecting cylindrical portions 42 of this bridging contact are adapted to engage the fixed contacts 44, 44 which are insulated from and supported by the parallel side walls 27, of the U-shaped portion 26 of housing 14.

The contacts 44, 44 are connected to suitable connectors 46 for receiving conductors which connect the switch in a circuit.

At a point between the axis of the switch arm sector 34 and its periphery 41, this switch arm is provided with a transversely extending spring supporting post 48. The post is preferably provided with a pair of peripheral grooves 49, one adjacent each end, for receiving a loop 50 carried by the end of each spring 25. The other end of each spring 25 has its loop hooked through an aperture 51 in the fins 23 carried by dash pot piston 17.

Various forms of switch mechanism may be employed, and the one which has been selected to illustrate the invention is merely one of the forms which may be used.

15 The U-shaped housing portion 26 may have its side wall 27, provided with an oval aperture 52 extending upwardly from the location of the fixed contacts 44, 44 so that the oil which is projected toward the contacts may pass outwardly toward the right and left through these apertures.

20 The operation of the switch mechanism is as follows: When the shield 34 is in the position of Fig. 1, the fins 23 being below the pivot 36 of the shield 34, springs 25 pull the shield 34 downwardly so that the contact 38 engages fixed contacts 44, 44.

25 As the dash pot 17 moves upwardly, the fins 23 carry the left end of the springs 25 upwardly, and when the fins 23 pass the line of centers of post 48, pivot 36, and spring attachment 51, the spring 25 thereafter pulls upwardly on the shield 34, which snaps upward, breaking the circuit between contact 38 and contacts 44, 44. The shield 34 is then interposed between the fixed contacts 44, 44, and it continues upward until its upper edge 37 engages stop surface 31.

30 Upon the return movement of the dash pot piston 17, the closing of the switch is again accomplished with a snap action, and the springs 25 tend to hold the switch closed or open, depending upon the position in which they happen to be.

35 The piston 18 has a suitable clearance with respect to the cylinder bore 16 so that a predetermined amount of oil may escape around the edges 40 of the piston 17 to permit the armature 13 to move at a regulated velocity.

40 While the piston 17 is moving along the slots 24, oil is projected through these slots toward the contacts of the switch to assist in quenching the arc. The slots 24 terminate short of the end of the piston bore 16 so that after the piston passes the end of the slots 24 the escape of oil from the space above the piston is greatly diminished as it is limited to the oil which escapes between the edges of the piston and the wall of the bore 16. Thus the upper end of the cylinder is utilized for cushioning the shock of movement of the piston, armature, and associated parts. These parts are also brought to a quick stop.

45 The armature 13 is carried at its upper end by an extension rod 53, which also serves to support a plurality of valve members. Rod 53 is mounted in a cylindrical socket 54 in the armature 13 and secured by a transverse rivet 55.

50 Above the armature 13 the rod 53 supports an oil pumping bushing 56 which has a sliding fit in a bore 57 in the housing 14. The oil pumping bushing 56 is secured to rod 53 by means of a transverse rivet 58, and is provided at its upper 55 end with a plane surface 59 serving as a cut-off valve with respect to the transverse conduit or port 60.

55 The upper casting 61 comprises a metal member provided with a tubular portion 62 having its end wall 63 provided with a cylindrical bore 64.

The bore 64 has a sliding fit with a cylindrical portion 65 on the rod 53, and the rod has an upwardly tapered portion 66 which ends in an abrupt shoulder 67 above, and tapers to the size of the cylindrical portion of rod 53 at the point 68. The location of these parts is such that when the shoulder 59 closes the port 60, the shoulder 67 passes the upper surface 69 on the tubular housing 61 and permits the escape of oil around the tapered portion 66 of extension rod 53.

The upper housing 61 is provided with a lateral tubular extension 70 which contains the conduit 60, and may terminate in a threaded bore 71 closed by a screw plug 72. This bore may serve as a clean-out opening by removal of the screw plug 72.

Bore 60 communicates with a downwardly extending port 73 which is closed by a ball valve 74 which permits oil to enter the port 73 but prevents its exit. A pin 75 above the ball valve 74 prevents the ball 74 from leaving its seat, except for a predetermined movement. The conduit 60 also communicates with an upwardly extending bore 76 which is closed by a gravity actuated ball valve 77, also having a pin 78 to limit its upward movement.

Tubular extension 70 is provided with a circular plate 79 on its upper side, to which is attached another cylinder 80 by means of screw bolts 81. The cylinder 80 has an inner cylindrical wall 82 for engagement with a piston 83 carried by a piston rod 84. The wall of cylinder 80 has an enlarged outlet bore 85 located at a point just below the dash line 86, which indicates the second position of this piston. The dot line 87 below the enlarged outlet port 85 indicates the first position of piston 83. At its upper end the cylinder 80 has a small outlet port 88.

Piston 82 and cylinder 80 constitute an integrating or counting device for counting the number of opening operations before the switch is locked in open position.

The piston rod 84 is provided on its end with a clevis 89 for attachment to a time delay lock-out mechanism, and the extension rod 53 is provided with a clevis 90 on its upper end for attachment to a manual operation lever.

The tank 9 in which the automatic circuit recloser mechanism is immersed may be provided with a cover 95, which may be secured to the tank 9 by means of suitable bolts or other fastening means. The tank 9 being cylindrical, the cover 95 is also provided with a circular base 96 having a depending drip flange 97 which is located outside the wall of tank 9.

The circular base 96 preferably supports a substantially rectangular housing portion 98, which has a pair of flat upwardly projecting walls 99, 100 and a partially cylindrical end wall 102, Figure 2. The other end wall 101 of the rectangular housing 98 extends diagonally upward to the top 103, from the edge of the base 96 and on either side of the housing 98 and may be the usual circular formations, apertured to receive the insulators which project from the cover (not shown).

The walls 100-102 support the integral top 103 of the housing 98, and the housing has an aperture 104 in its side wall 99 for passing the operating shaft 105. Top wall 103 may have a pair of depending bearing lugs 106, 107 (Figure 2) having bearing apertures 108, 109 for the shaft 105.

The shaft 105 (Figure 2) supports a lock-out arm 110, comprising a cast metal member formed

with a hub 111 having a bore for the shaft 105, the hub being pinned to the shaft by a transverse rivet or pin 112. The lock-out arm 110 has a screw bolt 113 (Figure 1) fixedly secured in its free end, the screw bolt 113 being threaded into the lock-out arm 110 and passing through a slot 114 in the lock-out link 115.

Lock-out link 115 is confined on bolt 113 by engaging lock-out arm 110 on one side and by having the head of the bolt 113 engaging lock-out link 115 upon the other side. The lock-out link 115, as well as switch actuating link 116 (Figure 1) are made of suitable insulating material, such as a rag-filled phenolic stock, so that the mechanism carried by cover 95 is suitably insulated from the recloser located below the links 115, 116. The lower end of lock-out link 115 is pivotally secured to clevis 89 by a rivet or screw bolt 117.

The hub 111 of the lock-out arm 110 also supports a toggle extension 118 at a point opposite to the arm 110. Toggle extension 118 (Figure 3) comprises a flat radially extending member provided with a transverse pin 119, serving as an abutment for a toggle spring 120.

25 The toggle extension 118 preferably has a spring supporting portion 121, outwardly beyond the pin 119, for engagement in the end of the spring 120 whereby the spring is constantly seated on the toggle extension 118 against the pin 119. The spring 120 comprises a helical coil spring, the end turns of which are formed into a full circle, and at its opposite end the spring 120 is supported upon a cylindrical part 122 of a toggle lever 123.

35 Toggle lever 123 comprises the cylindrical spring guide 122, and also an annular flange 124 against which the spring 120 is seated. Beyond the spring seating flange 124, toggle lever 123 has an axially projecting knife-edge pivot 125, the end of which is seen in Figure 3. The knife-edge pivot 125 is pivotally mounted in a groove 126, which is formed in an inwardly extending lug 127 in the upper right-hand corner of the cover 95 (Figure 1).

40 The initial compression of the spring 120 tends to hold the knife edge 125 in its groove 126. Suitable stops 128, 129 may be provided above and below the lock-out arm extension 118 to limit the movement of this lock-out arm in both directions, for example, when the lock-out arm extension 118 engages the upper stop 128, the lock-out arm 110 is then in its normal contact closed position, but when the lock-out arm extension 118 engages the lower stop 129 and the toggle is 45 in the position of Figure 3 then the lock-out arm is in the position of locking the contacts in open position, and the toggle spring 120 is holding the lock-out arm 110 in its uppermost position.

In addition to the lock-out arm 110, the shaft 50 105 supports the plunger arm 130 (Figure 2) which is provided with a hub 131 mounted for free rotation on the shaft 105. At its free or outer end plunger arm 130 is connected by a screw bolt or suitable pintle 132 to the upper end 55 of insulating link 116. The lower end of insulating link 116 is pivotally connected by means of a screw bolt or rivet 133 to the clevis 90 carried by extension rod 53.

The plunger arm 130 has its hub 131 provided 60 with the axially extending segmental teeth 134, Figure 2, for engaging similar axially extending segmental teeth 135, carried by the hub 111 of lock-out arm 110. The angular size of the teeth 134, 135 may be substantially 60 degrees, and 65 there being four such teeth this leaves 60 degrees

of lost-motion space at 136 and 137 (Figure 5) between the teeth on lock-out arm 110 and the teeth on plunger arm 130.

In other words, there is a lost-motion connection between the plunger arm 130 and the lock-out arm 110, and the plunger arm 130 must move 60 degrees to take up the lost motion at 136, 137 between the teeth 134 and 135 before the plunger arm can actuate the lock-out arm 110. This 60 degree lost motion is sufficient to permit the automatic circuit breaking mechanism, including the extension rod 53, to move up and down to open or close the contacts of the automatic circuit recloser without affecting the lock-out mechanism provided by toggle extension 118, spring 120 and toggle lever 123, which is actuated to the lock-out position by the link 115 or moved back into the normal contact closed position by the same link moving in the opposite direction downward.

The shaft 105 is preferably provided at its outer end with a shock-absorbing manual actuating means. This may consist of a manual lever 138, which is provided at its outer end with a ring formation 139 for engagement with a suitable clamp stick or disconnect tool.

The manual lever 138 has a hub 140 at its inner end provided with a bore 141 for receiving shaft 105, upon which the manual lever 138 rotates freely. A transverse pin 142 located outside the manual lever 138, and passing through the shaft 105 holds the lever 138 on the shaft and serves as a thrust bearing. The shaft 105 also supports a leaf spring 143, which is carried by a suitable hub 144 that is pinned to the shaft by a transverse pin 145.

Spring hub 144, Figure 1, has a pair of radially extending lugs 146 separated by a slot 147 within which the leaf spring 143 is secured by means of a transverse friction pin 148. The leaf spring 143 is engaged adjacent its end by the oppositely extending lugs 149, 150, carried by manual lever 138.

Lugs 149 and 150 have a suitable clearance between them to permit the leaf spring 143 to bend. Manual lever 138 may have the axially projecting flanges 151 for housing the spring hub 144. The strength of the leaf spring 146 is such that it is strong enough to push the trunnions 119 and toggle spring 120 from one toggle position to the other, but the leaf spring 143 is not strong enough to hold the toggle arrangement against the action of the lock-out piston during the fourth operation of the cut-out.

Therefore, if the serviceman holds the lever 139 up to effect a closing of the contacts, this will close the contacts except during the fourth operation when the combined force exerted by the lock-out piston and the resistance of the toggle spring 120 will cause the manual shock-absorbing spring 143 to bend farther, and the lock-out piston will move the toggle into lock-out position against the force of the manual shock-absorbing spring 143.

While the operator is holding the manual lever 139 upward in the contact closing position, the shock-absorbing spring 143 permits the extension rod 53 and plunger arm 130 to move upward to open the contacts, if the overload still exists, after which the opening of the circuit will de-energize the solenoid coils, permitting the closing of the circuit again, and this will be repeated as well if the overload continues and as long as the serviceman holds the lever 139 upward.

Upon release of the lever 139 by the serviceman the contacts will stay open after the fourth operation, the toggle extension 118 having then been moved from the upper position of Figure 1 to the lower position of Figure 3, in which the toggle spring 120 holds the lock-out arm 110 in its upper position.

The operation of the manual control in connection with the automatic lock-out mechanism and the recloser mechanism is as follows: The contacts 44 and 38 of the circuit recloser are closed initially from the lock-out position of Figure 3 by pushing upward on the manual lever 138 at its ring 139 by means of a suitable tool. This moves the toggle 118, 120, 123 from the lock-out position of Figure 3 to the normal contact closed position of Figure 1, assuming that there is no fault existing on the line.

The angular movement of the shaft 105, which is brought about by this motion of the toggle from the position of Figure 3 to that of Figure 1, is sufficient to permit the movement of the plunger arm 130 downward in Figure 1 sufficiently to close the contacts.

When the lock-out lever is in the position of Figure 3 the teeth 135 on the lock-out arm engage the teeth 134 on the plunger arm 130, holding the plunger arm 130 upward to such a point that the spring pivot 51, for the snap spring 25, Figure 1, is above the line of centers 36 to 48, thus keeping the contacts open.

When the toggle has passed to the position of Figure 1, however, the plunger arm 130 may descend sufficiently to close the contacts, and this motion may be accomplished by merely raising the manual lever 138 when there is no fault on the line. When a fault appears on the line which results in a large increase of current flowing in the coil 11, the armature 13 is drawn upward lifting with it the extension rod 53 and the piston 17, and as the piston 17 rises it carries with it the end 51 of the snap spring 25 which opens the contacts at 38 with a snap action as soon as pivot 51 of the spring 25 passes the line of centers 35, 48.

The piston 17 then ejects oil out of the slots 24 to break the arc between the contacts, and the pump sleeve 56, engaging oil in the bore 57, forces a predetermined amount of oil past the ball check valve 77 into the space below the timing piston 83, which is raised to the first line 87 as a result of the first breaking of the circuit.

By the time the cut-off surface 59 of sleeve 56 has passed the port 60, so that oil can no longer pass into the timing cylinder, the shoulder 67 on extension rod 53 has passed the upper end of the bore 64, so that oil in the bore surrounding the extension rod 53 is released through the top bore 64 around the reduced portion 66 of the extension rod.

Each time such a circuit opening is brought about by the actuation of the armature, a measured amount of oil is pumped into the timing cylinder 80, and the piston 83 is successively raised to the levels 87, 86 and 88. There is a large discharge port 85 above the level 87 in the cylinder 80, permitting relatively quick action of the piston 83 for the first two operations, but after the second operation this discharge port 85 is closed by the piston 83.

On the third operation the oil above the piston 83 must be discharged through the relatively small discharge port 88, which involves a time delay by dash-pot action so that the operation of opening and reclosing the circuit, if the fault

still exists, takes a longer time on the third or fourth operation.

Many faults which occur on the line correct themselves very soon and, therefore, it is desirable to have such faults automatically open the circuit, but if the fault is corrected during the opening of the circuit it is desirable to have the circuit reestablished at once; thus the present mechanism is adapted to effect a reclosing after the first and second opening, practically immediately.

When any opening of the circuit occurs the solenoid coils 11 are deenergized, and the armature 13 tends to drop again by gravity, reclosing the circuit quite soon after it is opened, but after the second operation this reclosing is slower because of the time delay involved by the timing piston 83, which discharges oil from the space above it through a relatively small part 88 for the third or fourth operation.

During the first and second operations, and possibly the third, depending upon the way in which the parts are arranged, the timing piston 83 does not actuate the lock-out arm 110 because of the slot 114 which permits the link 115 to move upward a predetermined amount without actuating the lock-out arm 110.

When the lower end of slot 114 engages bolt 113, as, for example, on the third or fourth operation, then the timing piston 83 in its further motion raises the lock-out arm 110 against the force of toggle spring 120, moving the toggle from the position of Figure 1 to that of Figure 3, where the toggle spring 120 locks the contacts in open position. They are locked in open position because the lock-out arm 110 has been raised sufficiently so that its teeth 135 engage the teeth 134 on the plunger arm 130, and the plunger arm 130 is held upward in such a position that the contacts at 38 are held open.

The present manual mechanism gives an indication of the fact that the contacts are open because the manual lever 138 is down in the position of Figure 3, when the contacts are open. Assuming the contacts to have been locked open, with the parts in the position of Figure 3, the serviceman who sees that they are open, by means of the position of manual lever 138, may push the lever 138 upward by means of a suitable tool. This moves the parts from the position of Figure 3 to that of Figure 1, and permits the plunger arm 130 to move downward sufficiently so that the spring 25 moves to the position of Figure 1 and closes the contacts.

If there is a fault still existing on the line at this time the surge of current through the coils 11 will raise the armature 13 and extension rod 53, and link 116 will raise the plunger arm 130. 60 degrees of free movement is permitted for the plunger arm 130, and, in addition to this, such additional movement is permitted as is necessary by the shock-absorbing spring 143 so that the circuit will again immediately be opened even though the manual lever 138 is held upward.

The mechanism will open the circuit again and again while the manual lever is held closed, during the existence of a fault, and the contacts cannot be held closed because of the 60 degree lost motion between the plunger arm and the lock-out shaft, and because of the additional motion permitted between the manual lever and the lock-out shaft by the shock-absorbing spring 143.

After the fourth operation the spring 143 is strong enough to push the toggle arrangement from the position of Figure 3, open circuit, to the

position of Figure 1, closed circuit, but spring 143 is not strong enough to hold the toggle arrangement there, and after the fourth operation if the serviceman releases the lever 138 the contacts will be locked open with the parts in the position of Figure 3.

Referring now to Figure 7, this shows the manual controlling mechanism for a three-phase installation. In this case all three of the lock-out arms 110 will be pinned to a single shaft 105 in identical angular relation to each other. Then the link 115 on any phase can rotate its lock-out arm 110 clockwise, and all of the lock-out arms being fixed to the same shaft they will all be rotated clockwise simultaneously locking out all three phases at the same time.

It will thus be observed that I have invented an improved manual controlling mechanism for automatic circuit reclosers, which has the following advantages:

1. The mechanism is adaptable to a single unit or to a three-phase recloser, and when used on the latter a fault on any one of the phases will open the contacts on all three phases simultaneously, preventing damage to three-phase equipment.

2. The mechanism permits the contacts to be manually opened into the lock-out position.

3. When the mechanism is in the open lock-out position, it permits the time delay and sequence operation cylinder to reset itself only to the third or fourth pre-operation position as desired, so that when the unit is reclosed manually on the line, the sequence of operation begins with time delay rather than with an instantaneous operation.

4. The manual resetting means of this mechanism is trip-free, whereby, after lock-out, the contacts can be reclosed manually, but if a short circuit exists the contacts are reopened automatically even though the operator continues to hold the lever in the resetting position.

5. When the contacts are closed, under normal conditions the mechanism permits the sequence cylinder to reset for normal four-cycle operation, whether the contacts are closed manually after lock-out or whether they are reclosed automatically after a momentary fault of insufficient duration to cause lock-out.

50 While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

60 1. In a manual controlling mechanism for automatic circuit makers and breakers of the type having a time-delayed closing member biased by gravity to closed position and having an integrating device for lifting said closing member after a predetermined number of opening operations, the combination of a controlling shaft, rotatably mounted upon a container cover and having an end projecting from said cover, a metal hub fixedly secured to said shaft end and carrying a radially extending leaf spring, a handle member rotatably mounted upon said shaft end, said handle having opposing abutments for engaging the opposite sides of said spring, a lock-out arm fixedly secured to said shaft and having 65 its end connected to said integrating device by a

lost motion pin and slot, a switch controlling plunger arm rotatably mounted on said shaft and having its end connected to said closing member, opposed radial shoulders carried by the lockout arm and by the plunger arm and spaced angularly from each other to permit the arm closing member to move into open or closed position without moving the lockout arm and to permit said handle to move said closing member to open or closed position by moving through an angular range greater than said angular spacing, and lockout means acting on said lockout arm to hold the lockout arm in open circuit position.

2. In a manual controlling mechanism for automatic circuit makers and breakers of the type having a time-delayed closing member biased by gravity to closed position and having an integrating device for lifting said closing member after a predetermined number of opening operations, the combination of a controlling shaft, rotatably mounted upon a container cover and having an end projecting from said cover, a metal hub fixedly secured to said shaft end and carrying a radially extending leaf spring, a handle member rotatably mounted upon said shaft end, said handle having opposing abutments for engaging the opposite sides of said spring, a lockout arm fixedly secured to said shaft and having its end connected to said integrating device by a lost motion pin and slot, a switch controlling plunger arm rotatably mounted on said shaft and having its end connected to said closing member, opposed radial shoulders carried by the lockout arm and by the plunger arm and spaced angularly from each other to permit the arm closing member to move into open or closed position without moving the lockout arm and to permit said handle to move said closing member to open or closed position by moving through an angular range greater than said angular spacing, and lockout means acting on said lockout arm to hold the lockout arm in open circuit position, said lockout means comprising a toggle lever pivotally engaging said cover at one end, and pivotally engaging, with its other end, a toggle extension carried by said lockout arm, said toggle lever being spring biased out of toggle alignment position.

3. In a manual controlling mechanism for automatic circuit makers and breakers of the type having a time-delayed closing member biased by gravity to closed position and having an integrating device for lifting said closing member after a predetermined number of opening operations, the combination of a controlling shaft, rotatably mounted upon a container cover and having an end projecting from said cover, a metal hub fixedly secured to said shaft end and carrying a radially extending leaf spring, a handle member rotatably mounted upon said shaft end, said handle having opposing abutments for engaging the opposite sides of said spring, a lockout arm fixedly secured to said shaft and having its end connected to said integrating device by a lost motion pin and slot, a switch controlling plunger arm rotatably

mounted on said shaft and having its end connected to said closing member, opposed radial shoulders carried by the lockout arm and by the plunger arm and spaced angularly from each other to permit the arm closing member to move into open or closed position without moving the lockout arm and to permit said handle to move said closing member to open or closed position by moving through an angular range greater than said angular spacing, and lockout means acting on said lockout arm to hold the lockout arm in open circuit position, said lockout means comprising a toggle lever pivotally engaging said cover at one end, and pivotally engaging, with its other end, a toggle extension carried by said lockout arm, said toggle lever being spring biased out of toggle alignment position, said spring being a coil spring mounted on said toggle lever and compressed between said extension and a shoulder carried by the toggle lever.

4. In a manual controlling mechanism for automatic circuit makers and breakers of the type having a time-delayed closing member biased by gravity to closed position and having an integrating device for lifting said closing member after a predetermined number of opening operations, the combination of a controlling shaft, rotatably mounted upon a container cover and having an end projecting from said cover, a metal hub fixedly secured to said shaft end and carrying a radially extending leaf spring, a handle member rotatably mounted upon said shaft end, said handle having opposing abutments for engaging the opposite sides of said spring, a lockout arm fixedly secured to said shaft and having its end connected to said integrating device by a lost motion pin and slot, a switch controlling plunger arm rotatably mounted on said shaft and having its end connected to said closing member, opposed radial shoulders carried by the lockout arm and by the plunger arm and spaced angularly from each other to permit the arm closing member to move into open or closed position without moving the lockout arm and to permit said handle to move said closing member to open or closed position by moving through an angular range greater than said angular spacing, and lockout means acting on said lockout arm to hold the lockout arm in open circuit position, said lockout means comprising a toggle lever pivotally engaging said cover at one end, and pivotally engaging, with its other end, a toggle extension carried by said lockout arm, said toggle lever being spring biased out of toggle alignment position.

50 JAMES K. HARPER.
